MACHINE FOR REMOVING WRAPPERS

Ernest A. Hamwi, Detroit, Mich.

Application May 22, 1935, Serial No. 22,765.

10 Claims. (Cl. 107—7)

This invention relates to machines for removing wrappers from confections or other articles.

An object of the invention is to provide a machine having a support for receiving wrapped confections and the like, and having means for retaining the extended ends of the wrappers in a predetermined position, in combination with mechanism operative to engage said ends of the wrappers and to remove the wrappers from the confections, and also having means for discharging the confection from the support and into any receptacle, such as an ice-cream cone.

Other objects of the invention will be apparent from the following description, reference being made to the annexed drawings, in which—

Fig. 1 is a top plan view of my improved machine, the operating handle being in section.

Fig. 2 is a side elevation of the machine.

Fig. 3 is a vertical transverse sectional view of the machine showing the gearing that operates the lever mechanism controlling the wrapper removing devices.

Fig. 4 is a view showing the lever mechanism for operating the wrapper removing devices.

Fig. 5 is a side elevation of the gearing shown in Fig. 3.

Fig. 6 is an enlarged sectional view approximately on the line 6—6 of Fig. 1.

The machine comprises a supporting frame 1 provided on one side with a gear housing 2 and on the opposite side with a lever housing 3. Two parallel rods 4 and 5 are rigidly mounted in the upper end of the frame and are rigidly connected at the respective ends by fittings 6 each of which has an inwardly extended arm 7. A support for the confection or article to be unwrapped is rigidly secured to the upper end of the frame and, in the embodiment shown, said support comprises a cylinder 8 provided with two diametrically opposite vertical slots 9 extending downwardly from the upper end of the cylinder and terminating a short distance above the lower end of the cylinder. This is to say that the slots 9 (Fig. 3) do not extend the full length of the cylinder. A ring 10 is attached to the lower end of the cylinder below the lower ends of the slots 9, and has its inner periphery in continuation of the inner periphery of the cylinder 8, and is formed with an outwardly tapered inner wall 11 in its lower portion adapted to receive the upper end of a receptacle 12 which, as shown, is an ice-cream cone of conventional construction. The upper end of the cylinder 8 has attached thereto a pair of approximately semi-circular members 13 the ends of which terminate at the sides of the

slots 9 and are formed with diverging end walls 14. The members 13 have upwardly flaring inner walls 15 constituting guides whereby the wrapped confections will be guided into the cylinder with the extended ends 16 of the wrapper protruding through the slots 9 and seating upon the lower end walls of said slots, and thereby supporting the wrapped confection in the cylinder until the wrapper is removed.

A pair of slides 17 are mounted on the rods 10 4, 5 at opposite sides of the frame 1, and each of said slides has a gripper arm 18. The ends of the arms 18 are in approximate alignment with the slots 9. Each of the blocks 17 supports a pivoted gripper arm 19. The gripper arms 19 15 are mounted on vertical pivots 20 and are provided with inwardly extended operating arms 21, the upwardly extended ends 22 of which are engaged by the forks 23. The forks 23 are formed on the ends of levers 24 which are mounted on 20 pivots 25 secured to the blocks 17. The ends of the levers 24 opposite from the forks 23 are connected with springs 26 which tend to move the levers 24 in a direction to move the gripper arms 19 toward the gripper arms 18 in order to close 25 the gripper device. In their outward or unoperated positions, the forks 23 are engaged against the arms 7, and the gripper arms 19 are held away from the gripper arms 18 to permit any wrappers that had been engaged by the gripper devices 30 to drop.

Levers 27 have sliding pivotal connection 28 with the blocks 17. The levers 27 are mounted on pivots 29 and have their lower ends pivotally connected with the outer ends of links 30. The 35 links 30 extend through openings 31 into the housing 3 and have their inner ends pivoted to the upper and lower ends, respectively, of a lever 32 attached to a rocking axle 33 extending through the frame 1 and into the gear housing 2. 40

A pinion 34 is attached to the axle 33 in the gear housing 2, and is in permanent mesh with a gear wheel 35 rotatively mounted on a stud 36. A lever 37 has one end mounted on the stud 36 and is attached to the gear wheel 35 by a bolt 38 so that, when said lever is operated, the gear wheel 35 will be turned. The lever 37 extends through an opening 39 in the housing wall 2, and a link 40 pivoted to the outer end of said lever, and also to the lower end of a link 41. The upper end of the link 41 is pivoted to a link 42 mounted on a pivot 43 supported by the arm 44 of an angular operating lever 45. The lever 45 is rigidly attached to a pivot 46 mounted in a bracket 47 rigid on the upper end of the frame 1. An arm 48 is at- 55

tached to the pivot 46 and supports a vertically adjustable plunger 49 above the cylinder 8.

A rod 50 is supported by the bracket 47 in position so that the ends of said rod will be engaged by formed parts 51 on the levers 24 when the slides 17 are moved inwardly toward each other.

In operation, the lever 45 is moved in a clockwise direction (Fig. 3), thereby moving the plunger 49 upwardly and laterally so that the wrapped confection can be placed in the support, which is the cylinder 8, with the ends 16 of the wrapper extending through the slots 9 and seating on the lower end walls of said slots, thereby supporting the confection in the cylinder. The support or 10 ice-cream cone 12 is held at the lower end of the cylinder 8 in position to receive the confection after the wrapper has been removed from the confection and the confection discharged from the cylinder. This movement of the lever 45 15 turns the gear wheel 35, and thereby the pinion 34, and operates the lever 32, the links 30 and the levers 27, thereby moving the slides 17 inwardly toward each other and engaging the formed parts 41 against the ends of the rod 50. 20 When the formed parts 51 of the levers 24 are engaged against the ends of the rod 50, the gripper arms 19 are thereby moved away from the gripper arms 18 so that, when the wrapped confection is placed in the cylinder 8, the ends 16 of 25 the wrapper will extend between the respective arms 18 and the cooperating arms 19. The lever 45 is then moved in the opposite direction and, through the connections described, moves the slides 17 outwardly. Before the gripper arms 18, 30 19 move beyond the ends 16 of the wrapper, the formed parts 51 move away from the ends of the rod 50 and permit the springs 26 to operate the levers 24 and clamp the gripper arms 19 upon the ends 16 of the wrapper. This is because the 35 ends 16 extend a sufficient distance beyond the cylinder 8 to be engaged by the gripper devices before the gripper devices move beyond said ends. Continued outward movement of the gripper devices causes the forks 23 to engage the arms 7 40 and thereby open the gripper devices to discharge therefrom the wrapper sections that had been removed from the confection. Also, such operation of the lever 45 operates the plunger 49 against the upper end of the confection in the 45 cylinder 8, and said plunger pushes the confection into the upper end of the receptacle or cone 12. It will be understood that the wrapper consists of two sections of material, each section covering about one-half of the confection, and that 50 55 the respective sections of wrapper are removed by the respective gripper devices in the manner described.

It is now apparent that this invention is operative to remove wrappers from confections and the like, and that it is entirely unnecessary for the hands of the operator to contact with the confections since, when the confections are placed in the cylinder 8, only the wrappers come into contact with the hands of the operator.

The invention may be varied within the scope of equivalent limits without departure from the nature and principle thereof.

I claim:—

1. A machine for removing wrappers from articles comprising a support having diametrically opposite openings for the ends of the wrapper, gripper devices, mechanism for moving the gripper devices toward said support, means for causing the gripper devices to engage the ends of the

wrapper, and means for opening the gripper devices to discharge the wrappers therefrom.

2. A machine of the character described comprising a vertical cylinder having diametrically opposite slots extending downwardly from the upper end of the cylinder and terminating short of the lower end of the cylinder and adapted to receive the ends of a wrapper on an article placed in the cylinder, gripper devices, means for supporting said gripper devices for movement toward and from said cylinder, mechanism for moving said gripper devices toward and from said cylinder, and means for causing said gripper devices to engage the ends of the wrapper and to withdraw the wrapper from said support when said gripper devices are moved from said support.

3. A machine of the character described comprising a vertical cylinder having diametrically opposite slots extending downwardly from the upper end of the cylinder and terminating short of the lower end of the cylinder and adapted to receive the ends of a wrapper on an article placed in the cylinder, gripper devices, means for supporting said gripper devices for movement toward and from said cylinder, mechanism for moving said gripper devices toward and from said cylinder, means for causing said gripper devices to engage the ends of the wrapper and to withdraw the wrapper from said support when said gripper devices are moved from said support, and means for opening said gripper devices to discharge the wrappers therefrom.

4. A machine of the character described comprising a frame, an approximately vertical cylinder mounted in connection with said frame and having diametrically opposite vertical slots extending from the upper end of the cylinder downwardly and terminating short of the lower end of the cylinder for receiving the extended ends of a wrapper on an article placed in said cylinder, a pair of parallel rods supported by said frame, gripper devices supported by said rods for movement toward and from said cylinder, mechanism for moving said gripper devices toward and from said cylinder, and means for causing said gripper devices to engage the ends of the wrapper extending through said slots during initial movement of said gripper devices from said cylinder.

5. A machine of the character described comprising a frame, an approximately vertical cylinder mounted in connection with said frame and having diametrically opposite vertical slots extending from the upper end of the cylinder downwardly and terminating short of the lower end of the cylinder for receiving the extended ends of a wrapper on an article placed in said cylinder, a pair of parallel rods supported by said frame, gripper devices supported by said rods for movement toward and from said cylinder, mechanism for moving said gripper devices toward and from said cylinder, means for causing said gripper devices to engage the ends of the wrapper extending through said slots during initial movement of said gripper devices from said cylinder, and means for releasing said gripper devices from said wrappers during final movements of said gripper devices from said cylinder.

6. A machine of the character described comprising a support for an article having a wrapper, means whereby the ends of the wrapper will engage said support and support the article in connection with said support, and mechanism for engaging the ends of the wrapper and withdrawing the same from within said support and from around the article.

7. A machine of the character described comprising a support for an article having a wrapper, means whereby the ends of the wrapper will engage said support and support the article in connection with said support, mechanism for engaging the ends of the wrapper and withdrawing the same from within said support and from around the article, and means for disengaging said mechanism from said wrappers.
- 5 8. A machine of the character described comprising a cylindrical support for a wrapped article, said support having diametrically opposite slots through which the ends of the wrapper on the article extend, mechanism for engaging the 10 ends of the wrapper and withdrawing the same from within the support and from around the article, and means for discharging the article from said support.
- 15 9. A machine of the character described comprising a frame, two parallel rods supported by said frame, a cylindrical support for a wrapped article attached to said frame and having oppositely disposed slots for holding the ends of the wrapper extended, gripper mechanisms mounted on said rods for movement toward and from said support, mechanism for moving said gripper mechanisms toward and from said support, and means for causing said gripper mechanisms to engage the ends of the wrapper during movement of said gripper mechanisms from said support. 20
10. A machine of the character described comprising a frame, two parallel rods supported by said frame, a cylindrical support for a wrapped article attached to said frame and having oppositely disposed slots for holding the ends of the wrapper extended, gripper mechanisms mounted on said rods for movement toward and from said support, mechanism for moving said gripper mechanisms toward and from said support, means for causing said gripper mechanisms to engage the ends of the wrapper during movement of said gripper mechanisms from said support, and means for releasing said gripper mechanisms from the wrappers.
